UNITED STATES PATENT OFFICE.

BERT A. SLATER, OF SOUTH BEND, INDIANA.

TOURIST SIGN.

Application filed December 6, 1924. Serial No. 754,328.

This invention relates to an improved automobile tourist sign and seeks, among other objects, to provide a device which may be readily attached to a vehicle for displaying the name of the home city or town of the tourist as well as the name of the destination point.

The invention seeks, as a further object, to provide a sign embodying a front plate, a back plate, and a plurality of letter plates, and wherein the letter plates will all be clamped between the front and back plates to thus not only be securely held in position but also to be held against rattling.

And the invention seeks, as a still further object, to provide a sign wherein the letter plates may be readily assembled upon the front plate or removed therefrom.

Other and incidental objects will appear hereinafter.

In the accompanying drawings:

Figure 1 is a perspective view showing the manner in which my improved sign may be attached to a conventional license plate of a motor vehicle.

Figure 2 is an enlarged sectional perspective view through the sign.

Figure 3 is an enlarged detail sectional view on the line 3—3 of Figure 1, looking in the direction indicated by the arrows.

Figure 4 is a perspective view showing the parts of the sign disassembled but in proper relative position.

Figure 5 is a fragmentary perspective view showing one of the bolt receiving lugs on the front plate.

Figure 6 is an enlarged fragmentary elevation showing the manner in which the letter plates are assembled upon the front plate.

In carrying the invention into effect, I employ a front plate 10 which may be of suitable resilient sheet metal and formed thereon is a rearwardly directed rim flange 11 having pairs of oppositely disposed lugs 12 located near the ends of the plate. One of said lugs is shown in detail in Figure 5, and, as will be observed, said lugs and the plate are provided with registering slots 13. In conjunction with the front plate I employ a mating back plate 14 which is shaped to fit within the rim flange 11 and formed in the back plate are notches 15 to freely accommodate the lugs 12. As shown in Figure 4, the plates 10 and 14 are apertured near the corners thereof to receive bolts 16

connecting the plates with each other and, as shown in Figure 1, wing nuts are preferably employed in connection with these bolts so that the nuts may be readily removed to permit the separation of the plates.

As best shown in Figure 4 of the drawings, the plate 10 is provided with an upper pair of parallel slots 17 and a like pair of lower parallel slots 18. These slots extend throughout the major portion of the length of the plate and, at the right end of the plate, as seen in said Figure 4, the metal between the slots is cut away a short distance to define entrance openings 19 at the outer ends of which are oppositely directed notches 20. The pairs of slots 17 and 18 are provided to accommodate letter plates 21. These plates may also be formed of suitable resilient sheet metal and are preferably flexible. At their ends, the plates are offset to define rearwardly spaced oppositely directed flanges 22 and each of the plates is provided with a letter printed or otherwise imposed thereon. Accordingly, the desired plates may be readily selected according to the letters thereon and, as suggested in Figure 1, assembled upon the front plate 10 to make up the name of the home town and State of the tourist at the upper pair of slots 17 of the front plate as well as to make up the name of the destination point at the lower pair of slots 18 of said front plate. Between the pairs of slots 17 and 18, the front plate is, as shown, preferably provided with the word TO suitably imposed directly upon the face plate so that after the letter plates have been assembled upon the front plate, the sign will read correctly.

Attention is now directed to Figure 6 of the drawings, wherein I have shown a typical letter plate and have illustrated the manner in which said letter plate is engaged with the front plate. As will be observed, the flanges 22 of the letter plate are inserted through a pair of the notches 20, when the letter plate is flexed slightly and coincidentally shifted sidewise to rest within the adjacent pair of entrance openings 19. Thus, the flanges 22 of the letter plate are disposed behind the front plate so that the letter plate may then be shifted from said pair of entrance openings along the communicating pair of longitudinal slots x , x of the front plate to the desired position. A similar procedure is, of course, followed in removing the

letter plates so that, as will be seen, the letter plates may be readily assembled upon the front plate or removed therefrom. After the letter plates have all been mounted in position upon the front plate, the back plate 14 is then applied to overlie the flanges 22 of the letter plates, when the bolts 16 are inserted and the nuts tightened thereon for clamping said flanges between the plates. Thus the letter plates will be tightly held in position and rattling or vibration avoided. In addition to the bolts 16, bolts 23 may also be employed, as shown in Figure 1, for connecting the plates centrally between the rows of letter plates. However, attention is directed to the fact that even should the letter plates become loose, said plates cannot shift from the slots of the front plate to become accidentally lost.

In Figure 1 of the drawings, I have illustrated one way in which my improved sign may be mounted upon a motor vehicle. A conventional motor vehicle tire carrier is indicated at 24. This tire carrier is provided with the usual cross bar 25 upon which is mounted, in accordance with prevalent practice, one of the license plates of the vehicle as indicated at 26. As shown in Figure 3, the cross bar 25 is slotted to receive bolts 27 which secure the license plate and, in the instance illustrated, these bolts are inserted through the slots 13 near the upper edge of the sign so that said bolts also serve to secure the sign. Thus, the sign may be readily attached and, of course, the lower slots 13 of the sign may, if found more convenient, be employed in mounting the sign in lieu of the upper slots.

It is observed that a portion of the front plate 10 is disposed between the several pairs of parallel slots 17 and 18, as indicated at 17' and 18'. These portions 17' and 18' provide supporting members to engage the letter plates 21 and prevent rearward displace-

ment thereof, whereas the flanges 22 engage the rear side of the sign plate 10 and prevent forward displacement of the letter plates when the latter are placed in position. The cut away portions 19, at opposite edges of the supporting members 17' and 18', together with the notches 20 in the outer edges or walls of the respective slots 17 and 18, provide clearance for the offset flanged edges 22 of the letter plate 21 when placing them in position or removing them from the sign plate 10, as indicated most clearly in Figure 6.

Having thus described the invention, what I claim is:—

1. A sign plate provided with a pair of spaced parallel slots and with notches extending outwardly from the slots, the portion between the slots forming a supporting member which has opposite edge portions cut away adjacent the outwardly disposed notches to form therewith clearance spaces, and letter plates having opposite edge portions passing through the said slots and engaging the rear side of the plate beyond and adjacent the said slots, and having the intermediate portion engaging the front side of the said supporting member to prevent rearward displacement of the letter plates.

2. A sign plate having spaced parallel slots providing an intermediate supporting member and having opposite edge portions of the supporting member cut away to provide entrance openings, and having notches at the ends of the said entrance openings formed in the outer walls of the slots, and letter plates having offset edge portions to pass through the slots of the sign plate and engage the rear side thereof, the intermediate portions of the letter plate adapted to engage the front side of the said supporting member.

In testimony whereof I affix my signature.

BERT A. SLATER. [L. S.]
